UNITED STATES PATENT OFFICE

125,809

DESIGN FOR A DRESS ENSEMBLE

Sylvia Franklin, New York, N. Y.

Application January 11, 1941, Serial No. 97,981

Term of patent 3½ years

To all whom it may concern:

Be it known that I, Sylvia Franklin, a citizen of the United States, residing in New York city, in the county of New York and State of New York, have invented a new, original, and ornamental Design for a Dress Ensemble, of which the following is a specification, reference being had to the accompanying drawings, forming part thereof.

I claim:

The ornamental design for a dress ensemble, substantially as shown.

SYLVIA FRANKLIN.
